To all whom it may concern:

Be it known that I, Howard V. Pehrson, a citizen of the United States, residing at Twin Lakes Park, Paris, in the county of Edgar, State of Illinois, have invented a new, original, and ornamental Design for a Desk Calendar or the like, of which the following is a specification, reference being had to the accompanying drawings, forming a part thereof.

In the drawings:

Fig. 1 is a front elevational view of a desk calendar or the like showing my new design;

Fig. 2 is a view looking at the right hand end of Fig. 1;

Fig. 3 is a top plan view thereof.

The dominant features of the design are shown in full lines.

I claim:

The ornamental design for a desk calendar or the like, as shown and described.
